SIMON SNYDER, OF MUNCY, PENNSYLVANIA, ASSIGNOR TO SPROUT, WALDRON & COMPANY, OF MUNCY, PENNSYLVANIA, A CORPORATION OF PENNSYLVANIA.

CONTROLLING DEVICE FOR GYRATORY BOLTERS.

1,323,329.

Specification of Letters Patent.

Patented Dec. 2, 1919.

Application filed June 28, 1918. Serial No. 242,456.

To all whom it may concern:

Be it known that I, SIMON SNYDER, a citizen of the United States, residing at Muncy, in the county of Lycoming and State of Pennsylvania, have invented certain new and useful Improvements in Controlling Devices for Gyratory Bolters; and I do hereby declare the following to be a full, clear, and exact description of the invention, 10 such as will enable others skilled in the art to which it appertains to make and use the same.

This invention relates to gyratory sifters or bolting machines of the type in which the 15 sieve structure is suspended from the ceiling or overhead support by resilient rods or reeds and to which a gyratory movement is imparted by means of a driving shaft journaled in the sieve structure, and its objects are to provide a smooth and even 20 running gyratory movement of the sieve structure and to prevent or reduce to a minimum the jerking and irregular movements of the sieve with consequent vibrations and injury to the building, which is 25 incident to the use of devices of this character as heretofore ordinarily constructed. Other objects are to provide improved anti-friction bearings and means for suspending 30 the driving shaft therefrom with provision for universal movement of the shaft to permit a gyratory movement of the sieve structure and driving shaft journaled therein, together with an underneath controlling 35 device that will prevent excessive gyration or wabbling of the machine in starting and stopping.

The invention will first be hereinafter more particularly described, with reference 40 to the accompanying drawings, which form a part of this specification, and then pointed out in the claims at the end of the description.

In said drawings:—

45 Figure 1 is a side elevation partly in section of the driving mechanism and associated parts of a gyratory sifter or bolting machine embodying my invention;

50 Fig. 2 is a vertical sectional view on an enlarged scale, of the overhead anti-friction radial and end thrust bearing with means for suspending the driving shaft so as to permit a universal pivotal or swinging movement thereof;

Fig. 3 is a vertical sectional view also on 55 an enlarged scale of the underneath controlling device;

Fig. 4 is a transverse sectional view taken on the line 4—5 of Fig. 3, indicating the lower shaft section centered or centrally 60 disposed with respect to the thrust limiting flange, and,

Fig. 5 is a similar view taken on said line 4—5 showing the lower shaft section displaced laterally, or in starting position. 65

In said drawings, in which the same reference letters are used to denote corresponding parts in different views, the letter A may denote a portion of the sieve structure or frame, which may be of any suitable form such as ordinarily employed in this class of machines, and designed to be suspended from the ceiling by resilient rods or reeds such as are commonly used for this purpose. 70

The driving shaft B, is journaled within 75 the sieve structure, preferably in ball bearings, as shown, and has coupled thereto at its upper end, so as to permit a limited movement thereof in the direction of its length while imparting a rotary movement thereto, the lower end of a shaft section B¹, 80 which is suspended from the ceiling, or an overhead support, by means of a bracket or hanger C, having a depending tubular part c, of cup-like form, into which the upper end 85 of the shaft section B¹, extends. Said shaft section B¹, has secured thereon an anti-friction bearing D, which is preferably of the form known as the S. K. F. self-aligning ball bearing, consisting of two concentric rings, 90 one of which, in this instance the inner ring, has annular grooves or ball races therein, each group to a radius slightly larger than the radius of the balls, while the other or outer race is ground in the form of a section 95 of a hollow sphere, so that the balls are free to rotate at any angle within this spherical outer race to permit a swinging or universal

pivotal movement of the shaft. As shown, the upper end of the shaft section B¹ is 100 formed with a reduced extension on which is fitted a sleeve or collar b, which is preferably formed or provided with a reduced extension b¹, on which the inner bearing ring d is fitted, so as to rest upon the shoulder at the base of the reduced extension b¹, 105 and a nut b², is screwed upon the threaded end of the shaft section so as to clamp said

inner ring and the collar b , between it and the shoulder at the base of the reduced extension of the shaft; thus securing the radial bearing upon the shaft in such manner that it will partake of the longitudinal movements of the shaft, while the inner ring rotates therewith; the outer ring d^1 , being relatively stationary but adapted to slide in the direction of the length of the shaft to accommodate itself to the movements of the shaft. The shaft is supported or suspended upon an end thrust bearing D^1 , within and resting upon, a pendant tubular cup-like portion C^1 , of the hanger C ; said thrust bearing being preferably of the type known as the S. K. F. self-aligning thrust bearing, consisting of upper and lower rings d^2 and d^3 , having annular grooves in their confronting faces and balls running in said grooves; the under side of the lower ring being spherical and seated upon a correspondingly-shaped spherical surface of a base ring or washer d^4 , whereby the desired swinging or universal pivotal movement of the shaft is permitted. Said lower ring or washer d^4 , is seated upon an inwardly extending annular flange at the lower end of the tubular hanger member C^1 , which is formed or provided with an exterior annular flange c^1 , which may be secured to the pendant tubular portion c , of the hanger by set screws passed through apertures in said flange c^1 , and screwed into threaded holes or sockets in the lower end or part c , of the hanger.

As a means for lubricating the shaft bearing and imparting rotary movement to the shaft, I provide a pulley E , which may be formed or provided with a substantially semi-globular oil cup or vessel E^1 , inclosing the pendant tubular portion of the hanger and having a hub portion e , which is made fast on the shaft by means of a set screw e^1 , or other fastening device; said hub portion being provided with a suitable stuffing box, as shown, to prevent leakage of the lubricant down the shaft. For convenience in oiling the bearing, an oil pipe F , may have one end connected with an aperture through the upper wall of the tubular part of the hanger, and provided with a compression cup F^1 , on its free end.

The intermediate section B , of the driving shaft is preferably journaled in annular ball bearings within the frame structure, and has secured thereto an unbalanced weight or weights G , such as are commonly employed in gyrating machines, and is provided with a coupling member between it and the upper shaft section B^1 of substantially the same construction as the ball bearings and coupling member shown in a joint application of myself and one Lloyd C. Winegardner, Serial No. 150,057, filed February 21, 1917, and as such bearings and

coupling member form no part of my present invention further description thereof herein is deemed unnecessary.

In order to prevent the jerking and irregular movements of the sieve structure which results from excessive gyratory movement thereof when the machine is started or while it is being slowed down for stopping, with consequent liability to vibrate and injure the building, I provide an improved underneath controlling device, whereby such excessive gyration is prevented and a smooth and evenly running movement of the machine is produced in a much shorter space of time and with less vibration than is possible in using devices such as have heretofore been used for the same purpose. To this end, there is secured on the lower end of the shaft B , an eccentric pin or shaft section B^2 , and an eccentrically supported revoluble load or weight I , which projects from the shaft in the direction of the unbalanced weights G , and which load or weight during the rapid rotation of the shaft, is centered coincident with the axis of revolution, but thrown outwardly, in stopping and starting, by centrifugal force, in the direction in which the weights extend. The weight I , as shown, has an opening through its center into which the lower end of the shaft section B^2 , extends and is formed or provided with a tubular extension i which is co-incident with said opening. To prevent undue friction and permit longitudinal movement of the shaft, the lower end thereof is formed or provided with a reduced extension b^3 , on which is screwed a nut b^4 , between which and the shoulder at the base of said reduced extension is secured the inner ring or race member of an annular ball bearing D^2 , preferably of a well known type consisting of two concentric rings with grooves in their confronting surfaces and a series of balls therebetween running in said grooves; the outer ring being slidably fitted within the socket of the eccentrically supported weight so as to permit sidewise movement thereof longitudinally of the shaft. The depending tubular extension i of the weight I , enters a circular opening formed by a thrust limiting flange k , at the apex or top of a pedestal-like floor plate K , so as to contact therewith when thrown outwardly in stopping or starting and prevent lateral movement of the shaft beyond the point of contact. To eliminate or deaden the sound, a washer L , of wood or other suitable material, may be placed between the weight I and the top of the pedestal, and a strip M , of leather or other suitable material may be placed around the part i of the weight to facilitate rotation of the latter when it contacts with the thrust limiting flange and also to deaden the sound.

As will be seen, when the machine is at rest or has attained the desired speed of rotation, the eccentric pin and the load or weight thereon will be centered with the 5 pin co-incident with the axis of revolution, but in starting or stopping, the weight or load will be thrown outwardly by centrifugal force until the tubular pendant portion thereof contacts with the thrust 10 limiting flange *k* whereupon the weight or load, by virtue of such contact, will be caused to rotate in a direction opposite to the direction of rotation of the shaft, as indicated by the arrows in Fig. 5 of the drawings, with the result that the desired speed 15 of rotation will be attained and the shaft brought back to the center of revolution expeditiously, quickly, and noiselessly, owing to the counteracting forces generated by the 20 oppositely rotating weight and shaft, thus producing a smooth and evenly running motion without the jerking and irregular movements in starting and stopping which are incident to the use of machines of this 25 type, as heretofore ordinarily constructed.

Having thus described my invention, what I claim as new and desire to secure by Letters Patent, of the United States, is:—

1. A controlling device for gyrating machines comprising a stationary thrust limiting device having a circular opening therein, a driving shaft suspended from above and carrying at its lower end an eccentrically arranged pin or shaft section; said 30 shaft section carrying an eccentrically supported revoluble weight having a centrally disposed extension protruding into the opening through said thrust limiting device, said weight being journaled on said 35 shaft and adapted to rotate in a direction opposite to the direction of rotation of the shaft and to permit movement of the shaft in the direction of its length.

2. A controlling device for gyrating machines comprising a stationary floor plate of 40 pedestal-like form having a circular opening through its top to provide a thrust limiting flange, a driving shaft suspended from above and carrying at its lower end an eccentrically arranged pin or shaft section on which is secured a weight having a 45 centrally disposed extension protruding into said opening, said weight being journaled on said shaft section so as to rotate independently thereof and in an opposite direction thereto while permitting independent movement of the shaft in the direction of its length; there being an annular space separating said extension and surrounding 50 flange.

3. In a gyrating machine including a 55 flexibly suspended sieve structure and a driving shaft therefor, a controlling device comprising a revoluble eccentrically supported load or weight on the shaft and

means for limiting the outward throw of said weight beyond a predetermined point; said means consisting of a floor-plate having a circular opening therein and on which said weight is slidably and revolvably supported, 70 and a projection on said weight protruding into said opening; said means and weight co-operating to produce rotary movement of the weight in a direction opposite to the direction of rotation of the shaft. 75

4. In combination with a gyrating sieve structure and a driving shaft therefor, a controlling device comprising an eccentrically supported weight journaled on said shaft and having a pendant projection, and 80 a thrust limiting flange having a circular opening therein to receive said projection; said flange being adapted by rolling contact with said weight to produce a rotary movement thereof in a direction opposite to the 85 direction of rotation of the shaft.

5. In combination, a flexibly suspended sieve structure, a driving shaft therefor carrying an eccentrically arranged pin or shaft section, and an eccentrically supported load 90 or weight carried by and revolvable on said shaft section underneath said sieve structure, a circular thrust limiting flange on which said weight rests, said weight having a centrally disposed socket and co-incident portion projecting into the opening through said flange and said shaft having its lower end journaled in said socket. 95

6. In combination, a flexibly suspended sieve structure, a driving shaft therefor, and 100 an underneath controlling device consisting of a floor plate of pedestal-like form having a circular opening through its top, a weight resting on said pedestal having a tubular part projecting into said opening, said 105 weight having an opening therein co-incident with said tubular part, and an eccentric shaft section on which said weight is revolvably secured; said shaft section having an annular ball bearing thereon fitted in 110 said tubular portion of said weight; said bearing consisting of concentric rings with balls therebetween, one ring being carried by and rotatable with the shaft and the other ring being relatively stationary but slidable 115 sidewise longitudinally of the shaft.

7. In a gyrating machine, an underneath controlling device comprising a floor plate or pedestal having an annular thrust limiting flange at its top, a driving shaft having 120 an eccentrically arranged pin or shaft section depending therefrom carrying a weight revolvably mounted thereon and resting on said top, a sound deadening washer interposed between said weight and top, said 125 weight having a depending centrally disposed tubular extension protruding through said thrust limiting flange and an opening therethrough co-incident with said extension, a flexible lining encircling said exten- 130

sion, and an eccentric pin or shaft section having a bearing within the socket formed by said opening and tubular extension.

8. The combination in a gyrating machine, of a sieve structure freely suspended for gyration, a driving shaft having an intermediate section journaled in bearings carried by and centrally disposed within said sieve structure, eccentrically connected up-
10 per and lower shaft sections, an overhead support from which said upper shaft section is suspended with provision for universal pivotal or swinging movement thereof, said upper shaft section being coupled to
15 said intermediate section so as to revolve

therewith while permitting a limited movement thereof in the direction of its length, and said lower shaft section having a weight surrounding it and revolubly connected thereto, together with a thrust limiting 20 flange, and means whereby the shaft and weight are caused to rotate in opposite directions in starting and stopping.

In testimony whereof I affix my signature in the presence of two witnesses.

SIMON SNYDER.
